UNITED STATES PATENT OFFICE.

WILLIAM D. OSBORNE, OF PHILADELPHIA, PENNSYLVANIA, ASSIGNOR OF
ONE-HALF OF HIS RIGHT TO ALBERT B. SLOANAKER, OF SAME PLACE.

PROCESS OF PRODUCING, EMBELLISHING, AND RETOUCHING PHOTO-NEGATIVES.

SPECIFICATION forming part of Letters Patent No. 228,380, dated June 1, 1880.

Application filed November 24, 1879.

To all whom it may concern:

Be it known that I, WILLIAM DIXON OSBORNE, of Philadelphia, in the county of Philadelphia, in the State of Pennsylvania, have discovered and invented a new Process for Producing and Improving Photographic Negatives; and I do hereby declare that the following is a full, clear, and exact description thereof, sufficient to enable any one skilled in the art to make and use the same.

My discovery and invention consists of a process for making a photo-negative or improving and embellishing some other such negative from which photographs are taken in any of the usual methods. The negative may be formed on the usual plate-glass or other transparent material used for that purpose.

In carrying my process into effect I take a photo-negative plate and smoke it over a gas-burner or lamp until it has formed a sufficient deposit of soot to enable me to draw thereon. I then sketch the design in negative form upon the prepared surface with a brush or eraser, after which I again smoke it and work up the design which I have sketched, and so repeat the smoking and working until I have the strength and contrast I desire. To preserve permanently the design thus drawn on the photo-negative the surface is coated with a gum-varnish made from gum dissolved in benzine or turpentine. The negative is then complete and ready for printing from in the usual manner of photo-printing.

By this means I can improve and embellish any photo-negative taken in the usual manner; and, further, with brushes and erasers I can correct any imperfection, improve the lights and shades, and make any addition or alteration that I may desire, such as draw hair on the head, sharpen the features, tone down any objectionable lights, all of which can be done in such a manner as to harmonize thoroughly with the rest of the image. It is then varnished and ready for printing.

It is preferable that the original negative be taken on a medium-tint plain ground when a scenic background is to be added.

The deposit from the smoke of gas or naphtha, being more free from oily, gummy, and other

adhesive substance, is the best adapted to the purpose.

I am aware that on a glass plate having prepared thereon the engraver's black etching-ground a spectrum has been formed by a correct ruling-machine with diamond or other point and suitable edges, guides, or patterns, for the purpose of producing line-engravings from transparent photographs.

I am also aware that plain smoked-glass plates have been known and used in astronomy for the observation of an eclipse; that a smoked glass has also been used, with the aid of a pantograph or artificial human ear, for the purpose of visibly indicating the vibrations produced by the human voice; also, to visibly indicate the pitch of musical tones by means of the vibrations of the tuning-fork.

I do not claim a plain smoked glass to receive tracings, broadly; but

What I do claim as new, and desire to secure by Letters Patent, is—

1. As an improvement in the art of photography, the method described of softening or toning down negatives, and at the same time adapting them for retouching to cure original defects of the subject, or making changes in form, figure, or attitude of the same, and also for the artistic production of scenic effects, and which consists, essentially, in depositing on the surface of the plate, by means of smoke generated from the burning of gas, naphtha, kerosene, or other of the hydrocarbons, a coating of soot, lamp-black, or other suitable carbonaceous deposit, substantially as and for purpose hereinbefore specified.

2. A photo-negative having the ordinary silver or other picture upon it, and provided further with a smoke-deposit of variable thickness to retard or otherwise regulate the transmission of light through it, and having furthermore delineated upon its smoked surface an artistic design in the way of background protected by a transparent preservative coating, substantially as described.

WILLIAM DIXON OSBORNE.
